THE LIKECharles T. Breitenstein, Chicago, Ill., assignor to Raymond T. Moloney, Chicago, Ill.

Application April 7, 1950, Serial No. 9,026

Term of patent 14 years

(Cl. D34—5)

To all whom it may concern:

Be it known that I, Charles T. Breitenstein, a citizen of the United States and a resident of Chicago, Cook County, Illinois, have invented a new, original, and ornamental Design for a Housing for Bowling Games and the like, of which the following is a specification, reference being had to the accompanying drawings, forming a part hereof.

Fig. 1 is a front perspective view of a housing for bowling games showing my new design;

Fig. 2 is a fragmentary front perspective view thereof to enlarged scale;

Fig. 3 is a side elevational view;

Fig. 4 is a top plan view of the same; and

Fig. 5 is a front elevation of the same.

The characteristic features of my new design are shown in full lines.

I claim:

The ornamental design for a housing for bowling games and the like, as shown and described.

CHARLES T. BREITENSTEIN.
